UNITED STATES PATENT OFFICE.

FRANCIS A. GUDGER, OF NEW YORK, N. Y., ASSIGNEE TO THE ARLINGTON COMPANY,
OF NEW YORK, N. Y., A CORPORATION OF NEW JERSEY.

FACE-SHIELD.

1,202,513.

Specification of Letters Patent. Patented Oct. 24, 1916.

Application filed June 8, 1915. Serial No. 32,808.

To all whom it may concern:

Be it known that I, FRANCIS A. GUDGER, a citizen of the United States, residing in the borough of Manhattan, city of New York, county and State of New York, have invented certain new and useful Improvements in Face-Shields, of which the following is a specification.

The invention relates to a face shield which can be detachably secured at will in place on a hat brim.

As showing a specific embodiment of the invention reference is made to the drawing forming a part of this specification, in which drawing—

Figure 1 shows a hat with my improved face shield secured in place on the brim. Fig. 2 is a plan view showing a portion of the face shield and one of the clamps which are utilized to secure the shield to the hat brim. Fig. 3 is a vertical sectional view taken on the line 3—3 Fig. 2. Fig. 4 is a vertical sectional view taken on the line 4—4 Fig. 1. Fig. 5 is a view showing the construction of the body portion of the face shield where it is attached to the clamps.

The face shield comprises the body A and three spring clamps B which detachably secure the face shield in place on the brim C of a hat. The body A is made up of a thin flexible strip D of transparent celluloid which has a reinforcing band E secured to it along its marginal edge. This reinforcing band is preferably of celluloid which may or may not be transparent and it is secured directly to the thin transparent strip D by the application of heat and pressure so that the band and strip form a unitary structure.

From Fig. 3 it will be observed that the band E at the upper portion of the strip is somewhat wider than that portion of the band E which is at the side edges and bottom edge of the strip. The clamps B each comprise a pair of clamping jaws F which are forced toward clamping position and held together by means of the C-shaped spring G. These jaws have handles H whereby they can be opened and closed at will. The body A has perforations K extending through both the reinforcing band E and the strip D, and through these perforations the C-shaped spring G extends so that the clamps B, through the medium of said spring G, can serve as supports for the

body A. The body A is also cut out or recessed at L above each of the perforations K to provide a space for receiving therein a portion of the lower clamping jaw F, the position of the latter of which is indicated by the dotted lines in Fig. 5. This allows the upper portion of the body A to be brought close to the underside of the brim of the hat.

From a further inspection of Fig. 3 it will also be observed that the clamps B are adjustable as a whole relative to the body A and can readily adapt themselves relative to the body A so as to position themselves properly to clamp the brim of the hat without distorting the latter.

The face shield shown is particularly adapted to be secured upon the brims of hats, such as are worn by ladies when automobiling. It is for the purpose of protecting the face of the wearer when automobiling that this shield was constructed.

The improvements herein set forth are not limited to the precise construction and arrangement shown and described, as they may be embodied in various forms and modifications without departing from the spirit and scope of the invention.

What I claim is:

1. A face shield comprising a transparent strip of material having at its upper edge portion spring clamps for securing the transparent strip in place below a hat brim, the spring of each of said clamps passing through the upper portion of the transparent strip and serving as the medium through which the strip is supported by said clamps, which clamps are adjustable as a whole relative to said strip.

2. A face shield comprising a body and spring clamps for supporting the same, said body being formed of a strip of transparent celluloid and a reinforcing band of celluloid secured to the strip along its marginal edge, each of the clamps having a member that passes through the upper portion of said strip and that portion of the band extending along the upper edge of said strip whereby the body can be directly supported from said clamps, said clamps being adjustable as a whole relative to said body.

3. A face shield comprising a strip of transparent celluloid having along its margin a reinforcing band of celluloid which is secured directly to the celluloid strip, and

2

spring clamps having members which pass through said reinforcing band, said clamping members being so constructed that the members thereof which pass through said 5 reinforcing band can be positioned relative to the transparent strip in such a manner that the clamps can be attached to a hat brim.

4. A face shield comprising in combination a flexible strip of transparent material 10 and a plurality of spring clamping means for securing the flexible strip to a hat brim, said clamping means each being adjustable relative to the flexible strip whereby the 15 clamping means can be properly positioned to be attached to a hat brim.

5. A face shield comprising a flexible strip of transparent celluloid having secured along its marginal edge a reinforcing band 20 and three spring clamps located along the upper portion of the celluloid strip for securing the shield to the brim of a hat, each clamp being adjustable relative to the flexible strip of transparent celluloid so that 25 the clamps can be properly positioned for securing to a hat.

6. A face shield consisting of a body and 30 spring clamps for detachably securing said body to the brim of a hat, said body comprising a transparent strip of celluloid

which is reinforced along its marginal edge by a band of celluloid that is secured directly to said strip, the clamps each comprising a pair of jaws that are forced toward clamping position by C-shaped 35 springs, each of said springs passing through a perforation which is in the body so that the latter can be supported by said springs.

7. A face shield consisting of a body and 40 spring clamps for supporting the body, said body comprising a transparent strip of celluloid which is bound by a reinforcing band of celluloid that is secured to the transparent strip, the body being also provided 45 with perforations and recessed portions located above the perforations, the spring clamps each comprising a pair of clamping jaws and a C-shaped spring for forcing said jaws toward each other, which spring enters 50 one of said perforations, each of said recessed portions being of sufficient length to receive a lower clamping jaw.

This specification signed and witnessed the 5th day of June, A. D., 1915.

FRANCIS A. GUDGER.
